ABSTRACT

The disclosure relates to a diaphragm sleeve which is rolled inside out in a tank by a motive fluid supplied to one side thereof to positively displace fluid at the opposite side of the diaphragm from the tank. At least one supporting ring engages either the inner or outer periphery of the sleeve to resist lateral buckling of the sleeve and which slides along the sleeve as the latter rolls inside out.

ROLLING DIAPHRAGM CONSTRUCTION

This invention relates generally to positive displacement, liquid expulsion systems in which a diaphragm is attached to the liquid containing tank and to a piston therein which is propelled by gas pressure through the tank to expel the liquid, and relates more particularly to an improved, reinforced diaphragm for such use and various other applications.

Diaphragms of this general type are particularly useful in the liquid propellant expulsion systems of packaged liquid rocket engines but their usefulness has been limited in that their flexibility decreases as their size (and gauge) increases to accommodate greater propellant volumes.

Analytical and experimental work has shown that the cylindrical length of the diaphragm is limited by the fact that the same pressure which acts on the piston, also acts laterally on the cylinder. In order to avoid buckling of the cylindrical diaphragm, the pressure which produces the piston movement must be less than the critical buckling pressure of the cylinder.

Accordingly, the main object of the present invention is to provide an improved diaphragm construction which permits the use of a cylindrical diaphragm of increased length in an expulsion system and hence enables an increased propellant or liquid volume which may be stored and expelled.

An important object of the present invention is to provide an improved diaphragm of the type described which is provided with reinforcing means to resist buckling of the cylindrical diaphragm during expulsion of the liquid.

Another important object of the present invention is to provide a hermetically sealed, rolling metal diaphragm for piston propellant expulsion in package liquid rocket engines in which resistance to cylindrical diaphragm buckling is provided by wires positioned at spaced points in peripheral contact with the diaphragm.

Other objects and advantages of the invention will become apparent during the course of the following description.

In the drawings, several embodiments of the invention are shown. In these showings:

FIG. 1 is a fragmentary, central, longitudinal sectional view of a liquid expulsion apparatus in the storage position showing the tank for the liquid to be expelled, the expelling piston, the cylindrical diaphragm hermetically sealed to both the piston and the tank, and the reinforcing means for the diaphragm;

FIG. 2-6 are fragmentary, sectional views of the different forms of the reinforcing means;

FIG. 7 is a view similar to FIG. 1 and showing means for moving the reinforcing means toward the expulsion end of the tank during expulsion; and

FIG. 8 is a view similar to FIG. 7 but showing the diaphragm completely rolled back and the reinforcing means collected and compressed thereby at the discharge end of the tank.

Referring to the drawings, numeral 10 designates a liquid expulsion apparatus as a whole which comprises a cylindrical tank 12, a piston 14, a diaphragm 16, and one form of reinforcing means 17.

The tank 12 is provided with ends (hemispherically shaped as shown) 18 and 20 and intermediate its length, one end of the cylindrical diaphragm 16 is hermetically sealed thereto as at 22. The tank end 18 is

provided with an inlet 24 for the admission of a gas or other pressurizing medium into the tank to act on the piston 14 and force it through the tank to abut the other end wall 20. The liquid filling the tank to the right of the piston is expelled through a discharge port 26 which may be provided with a burst disc, etc. 28.

The piston 14 to which the other end of the cylindrical diaphragm is hermetically sealed, may be formed of aluminum or other lightweight metal and is shaped 10 (hemispherical as shown) to conform with the shape of the tank ends 18 and 20 to afford a maximum of volumetric and expulsion efficiency.

The diaphragm 16 comprises a cylindrical shell in which sufficient resistance to buckling by the lateral 15 and radial pressures of the pressurizing medium, is provided by reinforcing means provided at spaced points along the length of the cylindrical diaphragm 16 and designated by numeral 17 in FIG. 1, which comprises rings circular in cross-section which engage the inner 20 surface of the diaphragm and mechanically strengthen it against the buckling pressure of the pressurizing medium.

It will be appreciated that the reinforcing rings may be positioned exteriorly of the diaphragm 16 as shown 25 in FIG. 2 wherein reinforcing ring 34 is fixed to the diaphragm by welding, glue, etc. 36, and that the rings 34 may be only partially exterior of the diaphragm by being fixed to a circular indentation 38 formed in the diaphragm as shown in FIG. 3. Similarly, as shown in 30 FIG. 4, the rings 34 may be positioned so as to engage the inner surface 40 of ribs formed in the diaphragm.

Further, the reinforcing rings which may be formed 35 of any desired material and whether engaging the interior or exterior surface of the diaphragm 16, may be of any desired cross-sectional shape such as triangular, rectangular or square as shown at 42 in FIGS. 5 and 6 in which case, the indentations or ribs where employed in connection with the rings are somewhat elongated to take care of the dimensions of the particular shape as at 44 in FIG. 6.

The operation of all forms of the invention is essentially the same. Pressure fluid from a suitable source is admitted to the tank 12 by way of the inlet port 24 to 45 act against the liquid expelling piston 14 and move it to the right to expel the liquid in the tank through the discharge port 26 when the built-up pressure bursts the disc 28.

As the piston 14 moves to the right toward the tank end 20 expelling the liquid in the tank, the thin flexible diaphragm 16 which acts as a seal between the pressurizing medium and the liquid is rolled backwardly 180° toward the right and the reinforcing rings if exterior and fixed move along therewith and if interior and not fixed, will move with the involution of the cylindrical diaphragm as it moves toward the expulsion end of the tank with the piston 14 until the piston assumes the position shown in FIG. 8 at the completion of liquid expulsion.

The disclosure of FIGS. 7 and 8 embodies the same principle of the invention as set forth above but employs a helical spring 45 which is preferably made of wire of any desired cross-section, and is fixed to the interior of the diaphragm 16. Alternatively, it may be fixed to the exterior of the diaphragm as suggested in FIGS. 2 and 3 or merely engage the interior as suggested in FIG. 1.

In the form of the invention shown in FIGS. 7 and 8, the diaphragm 16 is provided adjacent the piston 14 with a series of radially disposed inwardly projecting circumferentially spaced pins 46. During operation of this form of the invention, as pins in the cylindrical diaphragm 16 traverse the involution, they come in contact with the upstream or left end of the helical spring 45. Continued movement of the piston 14 causes the helical spring to compress until, as shown in FIG. 8, it is fully compressed when the piston 14 reaches the end of the liquid expulsion step. The pins are placed sufficiently forward on the diaphragm so that the piston 14 can reach the end of its expulsion stroke before the helical spring becomes fully compressed.

It will be appreciated that the rings of FIGS. 1, 4, 5 and 6 may be substituted for the helical spring 45 at the substantially uniformly spaced intervals disclosed and that during the liquid expulsion stroke of the piston 14, the pins 46 contact each ring, in turn, and push it toward the discharge port or outlet of the tank so that at the end of the piston's liquid expulsion stroke, the rings also are in contact with each other as shown in FIG. 8.

As the diaphragm 16 rolls back on itself, its diameter must decrease so that the inner fold or layer can slide by the original outer layer or wall. This reduction in diameter takes place automatically with a corresponding change in the wall thickness and/or elongation of the diaphragm. When the rings 17, 34, 42 or 45, either individually as in FIG. 1 or as coils of a continuous spring as in FIG. 7, are attached to the diaphragm they have substantially the same thickness as the diaphragm wall and act in the same manner as the diaphragm. In other words, the rings will flow through the other rings by a reduction in diameter with a flow of the material to produce a greater cross sectional area at a smaller ring diameter.

It is to be understood that the forms of the invention herewith shown and described are to be taken as preferred examples of the same and that various changes in the shape, size and arrangement of parts may be resorted to without departure from the spirit of the invention or the scope of the subjoined claims.

What is claimed is:

1. The combination with a liquid expulsion tank having a piston movable therein by a pressurizing medium from one end of the tank to the other to expel the liquid therefrom; of a flexible diaphragm having a continuous wall hermetically sealed at its ends to the peripheral wall of the tank and to the outer periphery of the movable piston, said diaphragm being rollable backwardly within itself by said piston upon liquid expelling movement thereof, and reinforcing means engaging said diaphragm along its length to strengthen it against buckling by the pressurizing medium acting on the piston comprising at least one transversely disposed ring engaging a periphery of said diaphragm and slideable along said diaphragm as the latter is turned inside out.

2. The combination recited in claim 1 wherein said reinforcing means comprises at least one transversely disposed ring engaging the inner periphery of said diaphragm and slideable along the diaphragm.

3. The combination recited in claim 2 wherein said reinforcing means comprises a plurality of rings engaging said cylindrical diaphragm at spaced points along its length, and each ring being circular in cross-section.

4. The combination recited in claim 2 wherein said rings are rectangular in cross-section.

5. The combination recited in claim 1 wherein said diaphragm is a metallic sleeve and said reinforcing means comprises transversely disposed metal rings attached to the outer periphery of said diaphragm and adapted to turn from the exterior to the interior of said diaphragm sleeve as the latter turns inside out.

6. The combination recited in claim 1 wherein said reinforcing means comprises a helical spring having its individual coils engaging the inner periphery of said diaphragm at spaced locations and slideable therealong as it rolls along the tank.

7. The combination recited in claim 2, and means projecting from the periphery of said diaphragm adjacent the piston and rollable back therewith to engage said rings and move them toward the other end of the tank.

8. The combination recited in claim 6, and means projecting from the periphery of said diaphragm adjacent the piston and engageable with said spring to compress it upon rolling back movement of said diaphragm.

9. The combination recited in claim 1 wherein said diaphragm is a metallic sleeve and said reinforcing means comprises a helical metallic spring having its coils attached to the outer periphery of said diaphragm adapted to turn from the outer periphery to the inner periphery of the diaphragm as the latter turns inside out.

10. The combination with a liquid expulsion tank having a piston movable therein by a pressurizing medium from one end of the tank to the other to expel the liquid therefrom; of a flexible cylindrical diaphragm hermetically sealed at its ends to the inner periphery of the tank and to the outer periphery of the movable piston, said diaphragm being rollable backwardly within itself by said piston upon liquid expelling movement thereof and said cylindrical diaphragm including circular indentations at spaced points along its length, and reinforcing rings attached to said indentations to strengthen said diaphragm against buckling by the pressurizing medium.

11. The combination recited in claim 10 wherein said diaphragm has circular ribs at spaced points along its length, and said reinforcing rings engaging the inner periphery of said ribs to strengthen said diaphragm against buckling by the pressurizing medium.
